NONSLIP WRENCH

Filed Aug. 7, 1950

UNITED STATES PATENT OFFICE

2,601,064

NONSLIP WRENCH

Peter Charles Snyder, Shickshinny, Pa.

Application August 7, 1950, Serial No. 178,063

8 Claims. (Cl. 74—156)

1

The invention relates to a safety non-slip ratchet wrench for automobile transporting trucks.

With the ordinary spanner wrench, customarily employed for engaging the ratchet wheel of the winding shaft or winch for tightening the chains or cables for securing a plurality of automobiles to an automobile transporting truck, there is nothing to prevent side slip of the spanner and frequently when heavy pressure is applied the spanner slips sidewise, which not only often results in injury to the person using the spanner but also damage to the automobiles.

It is, therefore, an object of the invention to provide a simple practical and efficient non-slip ratchet wrench of strong and durable construction, adapted to enable heavy pressure to be applied for rotating the winding shaft or winch without liability of side slip of the wrench otherwise becoming disengaged from the associated ratchet wheel.

A further object of the invention is to provide a non-slip ratchet wrench of this character which will afford greater freedom of movement for rotating the winding shaft and in which heavy operating pressure will result in a tighter gripping of the ratchet wheel by the wrench.

With the above and other objects in view, the invention consists in the construction and novel combination and arrangement of parts herein-after fully described, illustrated in the accompanying drawings and pointed out in the claims hereto appended, it being understood that various changes in the form, proportions, and minor details of construction, within the scope of the claims, may be resorted to without departing from the spirit or sacrificing any of the advantages of the invention.

In the drawings:

Fig. 1 is a plan view of a non-slip ratchet wrench constructed in accordance with the present invention;

Fig. 2 is a side elevation, partly in section, showing the head portion of the ratchet wrench applied to a winding shaft;

Fig. 3 is a transverse sectional view taken on the line 3—3 of Fig. 2;

Fig. 4 is an enlarged detail perspective view of one end of the winding shaft illustrating the arrangement of the ratchet wheel and safety collar with which the ratchet wrench cooperates;

Fig. 5 is a detail perspective view of one of the pawls of the ratchet wrench;

Fig. 6 is a detail view of a portion of the auto-

2

mobile transporting truck and illustrating the arrangement of the winding shaft or winch;

Fig. 7 is a detail transverse sectional view, partly in elevation, illustrating the manner of mounting the winding shaft or winch.

In the accompanying drawing in which is illustrated the preferred embodiment of the invention, the safety non-slip ratchet wrench consists of a bar 1 providing at one end a handle portion 2 and having a head 3 at the other end consisting of an enlargement provided with a substantially keyhole shaped opening 4 disposed longitudinally of the head and consisting of an enlarged circular outer portion 5 and an inner reduced portion 6 defined by parallel side walls 7 and an approximately semicircular end wall 8. The head is provided at opposite sides with ears 9 and 10 to which are pivoted pawls 11 and 12 located at the inner side face of the head. The pawls 11 and 12 are mounted on pivot bolts 13 and 14 having smooth pivot portions and provided at one end with a head and having a nut 15 or 16 for engaging the threads of the bolt.

When the ratchet wrench is applied to the winding shaft or winch 17 the pawl 11 engages the teeth 18 of a supplemental ratchet wheel 19 mounted on the winding shaft and suitably secured thereto adjacent an inner collar 20 which spaces the supplemental ratchet wheel from the conventional ratchet wheel 21 of the winding shaft or winch. The conventional ratchet wheel 21 is engaged by a gravity acting pawl 22 mounted on a suitable pivot 23 of one of the frame members 24 of the truck 25. The pawl 22 which is gravity acting is provided with a suitable handle 26 for enabling it to be readily disengaged from the ratchet wheel when it is desired to remove the automobiles carried by the transporting truck.

When the non-slip ratchet wrench is applied to the winding shaft it is arranged between the supplemental ratchet wheel 19 and an outer collar 27 spaced from the supplemental ratchet wheel to provide an annular groove 28 to receive the reduced inner bearing portion 6 of the key-hole shaped opening of the head of the ratchet wrench. The reduced inner portion 6 of the key-hole opening is of a width to receive the winding shaft at the groove 28 and the outer safety collar 27 is of greater diameter than the width of the reduced portion 6 of the keyhole opening so that when the ratchet wrench is applied to the winding shaft, as illustrated in Figs. 2 and 3 of the drawing, it cannot slip sidewise and the greater the pressure applied to the wrench for

rotating the winding shaft the tighter the wrench will grip the ratchet wheel without danger of any sidewise slip or injury to the operator or damage to the automobiles on the truck.

The pawl 11 is provided with a stop lug 29 which is arranged to engage the head of the ratchet wrench for limiting the inward movement of the pawl 11 so as to position the pawl properly for engaging the supplemental ratchet wheel.

The large outer portion of the keyhole opening enables the ratchet wrench to be passed over the outer collar 27 of the winding shaft and the parallel side walls of the smaller inner portion 6 of the opening 4 will guide the wrench and move the same longitudinally to bring the curved end wall into the groove 28 and into engagement with the winding shaft. By arranging the supplemental ratchet wheel and the collar at one end of the winding shaft, as illustrated in Fig. 7 of the drawing, beyond the conventional ratchet wheel 21, the ratchet wrench will have unlimited rotary movement to tighten the connecting lines 30 for firmly securing the automobiles 31 and 32 on the truck 25. The connecting lines may be chains or cables, diagrammatically illustrated in Fig. 6 of the drawings. The winding shaft is designed to be provided with one or more hooks 33 or other suitable means for enabling the lines 30 to be connected to the winding shaft and one or more guides 34 may be provided for guiding the lines when necessary.

The pawls 11 and 12 face inwardly and while only one will be engaged with the supplemental ratchet wheel 19, they provide for the facing of the teeth of the supplemental ratchet wheel in either direction to correspond with the arrangement of the teeth of the conventional ratchet wheel 21 so that should the conventional ratchet wheel 21 have its teeth facing in the opposite direction from that illustrated in the drawing, the supplemental ratchet wheel may be correspondingly positioned and the other pawl 12 will then engage with the supplemental ratchet wheel.

I claim:

1. A ratchet wrench for engaging a ratchet wheel of a winding shaft of a truck for transporting automobiles, said ratchet wrench comprising a bar having a handle portion at one end and a head at the other end having a longitudinal opening closed at both ends and defined by connecting side and end walls, one of the end walls being curved to conform to the configuration of the winding shaft and forming a bearing for the ratchet wrench, and a pawl pivotally mounted on the head and arranged to engage said ratchet wheel when the bearing surface is engaged with the winding shaft, said opening at the other end wall being enlarged and of a size to permit it to pass over a safety collar fixed to said shaft in spaced relation to the ratchet wheel to prevent lateral movement of the ratchet wrench when the bearing thereof is in engagement with the shaft.

2. A ratchet wrench for engaging a ratchet wheel of a winding shaft of a truck for transporting automobiles, said ratchet wrench comprising a bar having a handle portion at one end and provided at the other end with a longitudinally disposed substantially keyhole shaped opening, the reduced portion of the opening being of a size to fit the winding shaft and presenting a curved bearing surface for engaging the same and the enlarged portion of the opening being of a size to pass over a safety collar fixed to said

shaft in spaced relation with the ratchet wheel to prevent lateral movement of the ratchet wrench when the bearing thereof is in engagement with said shaft, and a pawl pivotally mounted on the head of said bar and arranged to engage the ratchet wheel when said curved bearing surface is engaged with the winding shaft.

3. A ratchet wrench for engaging a ratchet wheel of a winding shaft of a truck for transporting automobiles, said ratchet wrench comprising a bar having a handle portion at one end and provided at the other end with a longitudinally disposed substantially keyhole shaped opening, the reduced portion of the opening being of a size to fit the winding shaft and presenting a curved bearing surface for engaging the same and the enlarged portion of the opening being of a size to pass over a safety collar fixed to said shaft in spaced relation with the ratchet wheel to prevent lateral movement of the ratchet wrench when the bearing thereof is in engagement with said shaft, and a pair of pawls pivotally mounted on the head of said bar at the inner face thereof, one of said pawls being in position for engaging the ratchet wheel when the teeth thereof are facing in either direction.

4. A ratchet wrench for engaging a ratchet wheel of a winding shaft of a truck for transporting automobiles, said ratchet wrench comprising a bar having a handle portion at one end and a head at the other end having a longitudinal opening closed at both ends and defined by connecting side and end walls, one of the end walls being curved to conform to the configuration of the winding shaft and forming a bearing for the ratchet wrench and said opening at the other end wall being enlarged and of a size to permit it to pass over the safety collar fixed to said shaft in spaced relation to the ratchet wheel to prevent lateral movement of the ratchet wrench when the bearing thereof is in engagement with the shaft, and a pawl pivotally mounted on the head and arranged to engage said ratchet wheel when the bearing surface is engaged with the winding shaft, and a collar mounted on the winding shaft and spaced from the outer face of the pawl engaged ratchet wheel and forming a groove to receive the head of the ratchet wrench to prevent side slip of the same.

5. A ratchet wrench for engaging a ratchet wheel of a winding shaft of a truck for transporting automobiles, said ratchet wrench comprising a bar having a handle portion at one end and provided at the other end with a substantially keyhole shaped opening closed at both ends, the reduced portion of the opening being of a size to fit the winding shaft and presenting a curved bearing surface for engaging the same, a pawl pivotally mounted on the head of said bar and arranged to engage the ratchet wheel when said curved bearing surface is engaged with the winding shaft, and a collar mounted on the winding shaft and spaced from the outer face of the pawl engaged ratchet wheel and forming a groove to receive the head of the ratchet wrench to prevent side slip of the same and the enlarged portion of the opening being of a size to permit the ratchet wrench to pass over the collar and to be positioned at said groove whereby said reduced portion of the opening may be engaged with the shaft between the collar and the ratchet wheel.

6. In combination with a winding shaft having a ratchet wheel and provided with a collar

spaced from the ratchet wheel and forming an annular intervening groove, of a ratchet wrench having a head provided with a substantially key-hole shaped opening closed at both ends, the large portion of the opening being of a size to permit the head to pass over the collar and be positioned between the collar and the ratchet wheel and the reduced portion of the opening being of a size to fit the winding shaft in the groove between the ratchet wheel and the collar, and a pawl pivotally mounted on the head and arranged to engage the teeth of the ratchet wheel for enabling the ratchet wrench to rotate the winding shaft.

7. In combination with a winding shaft having in a ratchet wheel and provided with a collar spaced from the ratchet wheel and forming an annular intervening groove, of a ratchet wrench having a head provided with a substantially key-hole shaped opening closed at both ends and disposed longitudinally of the ratchet wrench, the large portion of the opening being located at the outer end thereof and of a size to permit the head to pass over the collar and be positioned between the collar and the ratchet wheel and the reduced portion of the opening being located at the inner end thereof and being of a size to fit the winding shaft in the groove between the ratchet wheel and the collar, and a pawl pivotally mounted on the head and arranged to engage the teeth of the ratchet wheel for enabling the ratchet wrench to rotate the winding shaft.

8. In combination with a winding shaft having a ratchet wheel and provided with a collar spaced from the ratchet wheel and forming an
